UNITED STATES PATENT OFFICE.

MAX M. COHN, OF SAN FRANCISCO, CALIFORNIA.

DISPENSING CABINET.

Application filed November 1, 1922. Serial No. 598,259.

To all whom it may concern:

Be it known that I, MAX M. COHN, a citizen of the United States, residing at the city and county of San Francisco and State of California, have invented new and useful Improvements in Dispensing Cabinets, of which the following is a specification.

This invention relates to a dispensing cabinet for toilet paper and the like.

10 The type of container involved herein is shown and described in a companion application executed by me of even date herewith, the same being in the form of a cubical container with two compartments, each compartment being capable of holding a package of interleaved sheets which are fastened together by a band. The sheets are inserted through an opening in the side wall of the cabinet and are dispensed through a slot in 20 the front wall.

The present invention has for its object to provide means for closing the opening in the side of the cabinet through which the packages of paper are inserted; also to effectually lock or fasten the closing means in place so that the paper will be protected against theft and likewise against the entry of dust or dirt.

One form which my invention may 30 assume is exemplified in the following description and illustrated in the accompanying drawings, in which—

Fig. 1 shows a perspective view of a cabinet embodying my invention.

35 Fig. 2 shows a plan view of the sheet of metal from which the cabinet is constructed.

In general the present cabinet is like the one shown in the companion case above mentioned and consists of a cubical container having two compartments, each adapted to receive a package of interfolded sheets. This container is preferably formed from a single sheet of material, as shown in Fig. 2, there being in the single sheet a front wall 10, top and bottom walls 11 and 12, back walls 13 and partition walls 14. The sheet is folded transversely along the dotted lines shown in Fig. 2 to bring the two end portions together at the middle of 45 the back, so that they project inwardly towards the front wall and form a partition, said end walls being fastened in any desired manner to the front wall. A side wall 15 is preferably made integral with the front 50 wall and bent into closed position and fastened therein, as by means of lugs 16

and openings 17. The front wall has a slot opposite each compartment through which the paper is dispensed, the package of paper being inserted through the open side of the 60 container.

In each compartment is a plate 18 having a slide 19 sliding upon a rivet 20, the latter being positioned to the back wall. The plate carries a flange 21 at its outer end 65 which serves to close the opening in the side of the compartment. The edge of the front wall adjacent the open side is beaded or curled, as shown at 22, and likewise the edge of the flange 21 has a bead or curl 23 70 adapted to spring under the beaded edge of the front wall when closed whereby it is retained in place. To spring it out requires pressure from the inside, and this can be done only by inserting the finger through 75 the slot in the front wall, which, of course, is not conveniently accomplished when the compartment is filled with paper.

Therefore the described arrangement provides a simple and inexpensive closing and 80 locking arrangement which will protect the paper against theft or the entry of dust or dirt.

Various changes in the construction and arrangement of the several parts herein 85 shown and described may be employed without departing from the spirit of my invention as disclosed in the appended claims.

Having thus described my invention, what I claim and desire to secure by Letters 90 Patent is:—

1. A dispensing cabinet for toilet paper and the like comprising a cubical container having an opening in its side through which a flat package of interleaved sheets may be 95 inserted and provided at its front midway between the top and bottom of the package with a slot through which the leaves are dispensed and a closure for the open side consisting of a plate slidably mounted for 100 horizontal sliding movement on the interior of the back wall and carrying a vertical flange to fill the open side while the leaves of paper are being dispensed through the front slot. 105

2. A dispensing cabinet for toilet paper and the like comprising a cubical container having an opening in its side through which a flat package of interleaved sheets may be inserted and provided at its front centrally 110 of the front of the package with a slot through which the leaves are dispensed, and

- a closure for the open side consisting of a plate slidably mounted on the interior of the back wall for horizontal movement and carrying a vertical flange to fill the side opening while the leaves of paper are being dispensed through the front slot, said flange being adapted to fit against the front wall with some degree of friction so that to open it pressure will have to be exerted in an outward direction. 40
5. A dispensing cabinet for toilet paper and the like comprising a cubical container having two compartments each adapted to receive, through an opening in the side wall of the container, a package of interleaved sheets, the front wall of the container being provided with a slot opposite each compartment and centrally thereof through which leaves are dispensed, the front, top, bottom, back walls and partition and one side being relatively stationary and formed of a single sheet of metal and independently slidable means for closing the opening in each of the compartments while the leaves of paper are being dispensed through the front slot. 45
10. A dispensing cabinet for toilet paper and the like comprising a cubical container having an opening in its side through which a flat package of interleaved sheets may be inserted and provided at its front centrally of the front of the package with a slot through which the leaves are dispensed, and a closure for the open side consisting of a plate slidably mounted on the interior of the back wall for horizontal movement and carrying a vertical flange to fill the side opening while the leaves of paper are being dispensed through the front slot, said flange being adapted to spring beneath the front wall when closed and to be opened by the pressure of the finger inserted through the slot. 50
15. A dispensing cabinet for toilet paper and the like comprising a cubical container having two compartments each adapted to receive, through an opening in the side wall of the container, a package of interleaved sheets, the front wall of the container being provided with a slot opposite each compartment and centrally thereof through which leaves are dispensed, the front, top, bottom, back walls and partition and one side being formed of a single sheet of metal and slid- 55
20. A dispensing cabinet for toilet paper and the like comprising a cubical container having an opening in its side through which a flat package of interleaved sheets may be inserted and provided at its front centrally of the front of the package with a slot through which the sheets are dispensed and a closure for the open side consisting of a plate having a slot slidably fitted on a guide fastened to the back wall of the container for horizontal movement and carrying a flange at its outer end to close the side open- 60
25. A dispensing cabinet for toilet paper and the like comprising a cubical container having two compartments each adapted to receive, through an opening in the side wall of the container, a package of interleaved sheets, the front wall of the container being provided with a slot opposite each compartment and centrally thereof through which leaves are dispensed, the front, top, bottom, back walls and partition and one side being formed of a single sheet of metal and slid- 65
30. A dispensing cabinet for toilet paper and the like comprising a cubical container having an opening in its side through which a flat package of interleaved sheets may be inserted and provided at its front centrally of the front of the package with a slot through which the sheets are dispensed and a closure for the open side consisting of a plate having a slot slidably fitted on a guide fastened to the back wall of the container for horizontal movement and carrying a flange at its outer end to close the side open- 70
35. A dispensing cabinet for toilet paper and the like comprising a cubical container having two compartments each adapted to receive, through an opening in the side wall of the container, a package of interleaved sheets, the front wall of the container being provided with a slot opposite each compartment and centrally thereof through which leaves are dispensed, the front, top, bottom, back walls and partition and one side being formed of a single sheet of metal and slid- 75
